(57) CLAIM

I claim the ornamental design for a purse with interior pattern, as shown and described.

DESCRIPTION

The file of this patent contains at least one drawing executed in color. Copies of this patent with color drawings will be provided by the Office upon request and payment of the necessary fee.

FIG. 1 is a first perspective view of a purse with interior pattern in accordance with my new design;

FIG. 2 is a front elevational view of the purse with interior pattern of FIG. 1, the rear elevational view being identical thereto;

FIG. 3 is a top plan view of the purse with interior pattern of FIG. 1;

FIG. 4 is a bottom plan view of the purse with interior pattern of FIG. 1;

FIG. 5 is a right side elevational view of the purse with interior pattern of FIG. 1, the left side elevational view being identical thereto; and,

FIG. 6 is a second perspective view of the purse with interior pattern of FIG. 1.
